UNITED STATES PATENT OFFICE.

VIRGIL E. FREDERICK, OF SPRINGFIELD, MISSOURI.

WINDOW-OPERATING DEVICE.

Application filed April 2, 1927. Serial No. 180,539.

The present invention relates to closure operators and has reference more particularly to a device for operating the windows of automobile doors of the closed types of vehicles.

One of the important objects of the present invention is to provide a window operating device, which includes a means for maintaining the window pane in any raised or lowered position, additional means being provided whereby the window pane may be readily and easily actuated for sliding movement in the window frame.

A further object of the invention is to provide a window operating device, which is simple in construction, strong and durable, and otherwise well adapted for the purpose for which it is designed.

Other objects and advantages of the invention will become apparent during the course of the following detailed description.

In the accompanying drawings, forming a part of this application and in which like parts are designated by similar reference characters throughout the several views:

Figure 1 is a view partly in section and partly in elevation of the window frame of an automobile door, showing the operating means for raising and lowering the window pane, the latter being shown in its lowered position.

Figure 2 is a transverse section taken approximately on the line 2-2 of Figure 1, looking in the direction of the arrows.

Figure 3 is a similar section taken approximately on the line 3-3 of Figure 1.

Figure 4 is a sectional view taken approximately on the line 4-4 of Figure 1, looking in the direction of the arrows, and

Figure 5 is a group perspective of the upper end of the lever and the handle which is associated therewith.

In the drawings, wherein for the purpose of illustration is shown the preferred embodiment of my invention, the numeral 1 designates the window frame of an automobile door or the like and adapted for vertical slidable movement within the upper portion of the frame is the window pane 2.

The usual guides for the side edges of the window frame are to be provided, and as the same forms no important part of the present invention, a detailed description and showing of the same is thought unnecessary.

The lower solid portion of the automobile door is formed with a chamber or compart-

ment 3, it being understood of course that one side of the door adjacent the compartment 3 is removable, to permit the installation of my improved window operating mechanism. A window sill 4 extends transversely across the window frame at the intermediate portion thereof and this window sill is formed with a longitudinal slot 5, which extends for the full length thereof, through which the window pane is slidable.

The window sill is formed with an additional longitudinal slot 6, adjacent the rear side of the frame 1 and the forward end of the slot extends to the intermediate of the sill as is clearly seen in Figure 3. The inner side edge of the sill is formed with the slot 7 and this slot communicates with the vertical slot 6 in the manner as clearly illustrated in Figure 4. The purpose of these slots will hereinafter be more fully described.

My improved window operating device comprises an elongated lever 8 which is disposed vertically within the compartment or chamber 3 and is fulcrumed at its lower end on the pivot 9. The upper end of this lever terminates at a point adjacent the window sill 4 and the upper end of this lever is formed with a longitudinally extending slot 10. Adapted for cooperation with the upper slotted end of the fulcrumed lever is the handle designated by the numeral 11, generally, the same comprising a flat strip 12, the upper end of which is twisted, as at 13 and the reduced upper end portion 14 is disposed at right angles to the body portion of the strip. The flat strip 12 of the handle 11 extends through the vertical slot 6 formed in the sill 4, so that the reduced upper end 14 will protrude above the upper face of the sill, in the manner as shown in Figures 1 and 4.

Extending laterally from the body portion 12 of the handle 11 are a pair of relatively short vertically spaced pins 15, the same being adapted to extend through the vertical slot 10 formed in the upper portion of the fulcrumed lever 8, and in which slot the pins are slidable vertically. An elongated pin 16 extends laterally from the same side of the body portion adjacent the twisted portion 13 and this pin 16 is operable in the slot 7 formed in the inner side edge of the window sill 4. The purpose of the pin and slot 16 and 7 respectively is to provide a means whereby the handle will

slide parallel to the window sill and to compensate for such sliding movement, the pins 15 cooperate with the slot 10. The projecting end of the handle provides a means for 5 swinging the fulcrumed lever 8 on its pivot 9 and this will be presently apparent.

A relatively short arm 17 is fixedly secured at its inner end to the lever 8 at a point adjacent the fulcrum or pivot 9 and as is 10 clearly illustrated in Figure 1, this relatively short arm is disposed at substantially right angles to the lever and extends rearwardly therefrom.

An elongated arm 18 is disposed substantially transversely within the chamber 3 and is pivoted at its free end adjacent the rear side of the frame 1 as is shown at 19. This elongated arm is disposed at an angle adjacent the fulcrumed end of the lever 8 and 20 the forward end of this arm is reduced as illustrated at 20 and arranged within the reduced forward free end of the arm are a series of spaced openings 21.

A substantially U-shaped clamp 22 is secured to the lower edge of the window pane 2 at the direct center thereof. Cooperating with this clamp 22 is the vertically extending lifting bar 23. This bar is pivotally secured at its upper end to the clamp as at 24 and the lower end of the lifting bar is pivotally secured to the forward end portion of the pivoted elongated arm 18, as at 25.

My improved window operating device further includes the provision of a link 26 35 which affords a pivotal connection between the rear end of the short arm 17 secured to the lower fulcrumed end of the lever 8 and the pivoted end of the transversely extending arm 18, in the manner as clearly shown 40 in Figure 1.

Also forming a part of the present invention is a counterbalancing means whereby the movable elements may be held in any adjustable position for maintaining the window pane in the desired raised or lowered 45 position. This counterbalancing means comprises a weight 27 which is slidable vertically in a channeled guide 28 provided therefor and this guide extends from the window sill 50 4 to the bottom of the frame 1 adjacent the forward side thereof in the manner as clearly shown in Figure 1. A cable 29 is secured at one end to the upper end of the weight 27 and is trained over a pair of pulleys 30 55 which depend from the window sill 4, it being understood, of course, that the side of the guide formed with an opening to permit the cable 29 to extend therethrough. The other end of the cable is secured to the 60 reduced forward end 20 of the pivoted arm 18, by means of a clevis 31 and this clevis cooperates with the spaced openings in permitting the cable to be adjustably secured to the free end of the cross arm 18.

65 The operation of my improved device may

be briefly stated as follows: When the window pane 2 is in its lowermost position, the handle 11 will be disposed at the rear end of the slot 6 in the window sill 4, and the parts will be in position in the manner shown in 70 the full lines in Figure 1. In order to raise the window pane the projecting end 14 of the handle is pushed forwardly, causing the fulcrum lever 8 to swing on its pivot and due to the manner in which the fulcrumed end 75 of the lever is connected to the pivoted cross arm 18, the latter will be swung upwardly to the position shown in the dotted lines, and simultaneously the lifting bar 23 will also move upwardly in a vertical plane and as a 80 result the window pane will be raised. The parts of the window operating device are maintained in any set position due to the weight 27 and the cable 29 which is secured to the forward end of the cross arm, and the 85 provision of this counter-balancing means will obviate the necessity of having to provide a pawl and ratchet structure in connection with the window sill and fulcrum lever, such as is now commonly provided on window operating devices used for raising and 90 lowering the window panes of automobile doors or windows.

The simplicity of my improved device enables the same to be readily and easily actuated and furthermore will, at all times, be positive and efficient in its operation. Also the construction of the present device will enable the parts to be readily assembled and installed without any difficulty and will furthermore be inexpensive. 95

While I have shown the preferred embodiment of my invention, it is to be understood that various changes in the size, shape and arrangement of parts may be resorted 100 to, without departing from the spirit of the invention or the scope of the appended claims.

What I claim is:

1. In combination with a window frame, 110 a sill extending transversely in the frame, and a window pane slidably mounted in the frame and through the window sill, a window pane operating device comprising a vertical lever fulcrumed at its lower end in the frame below the lower edge of the pane, a transversely extending arm fulcrumed at its rear end in the frame at a point above the fulcrumed part of the lever, a clamp secured to the lower edge of the pane at the center thereof, a vertical lifting bar pivotally secured at its upper end to said clamp and at its lower end to the forward free end of the fulcrumed arm, a relatively short arm fixedly secured at one end to the fulcrumed end of the lever and extending rearwardly therefrom at right angles thereto, a link pivotally connecting the outer end of the shorter arm to the fulcrumed end of the transversely extending arm, whereby the last men- 115 120 125 130

tioned arm and the lifting bar will be actuated to operate the sliding window pane, a handle associated with the upper end of the fulcrum lever and extending upwardly through the sill, said sill having formed with a slot in which said handle is operable to facilitate the actuation of the fulcrumed lever, and counter-balancing means for holding the window pane and the actuating means therefor in any adjusted position, said last mentioned means comprising a weight slidable vertically in the frame, a cable secured at one end to the weight and at its other end to the free end of the fulcrumed arm, and pulleys over which the cable is trained.

2. In combination with a window frame, and a window pane slidably mounted in the frame, a window operating device comprising a vertical lever, fulcrumed at its lower end within the frame, the lower edge of the window pane, the transversely extending arm fulcrumed at its rear end at a point above the fulcrumed lever, a clamp secured

to the lower edge of the same at its center 25 thereof, a vertical lifting bar pivotally secured at its upper end to the clamp and at its lower end to the forward free edge of the fulcrumed arm, the relatively short arm rigidly secured at one end to the fulcrumed end 30 of the lever and extending rearwardly therefrom, a link pivotally connecting the outer end of the shorter arm and to the fulcrumed end of the transversely extending arm, whereby its last mentioned arm and the lifting bar will be actuated to operate the sliding window pane when the end of the lever is moved, a channeled guideway disposed within the window frame, and a weight member adapted for slidable relation 35 with the guideway, and a flexible means connecting said weight member with the transversely extending arm to counter-balance the same during the movement of the operating device. 40 45

In testimony whereof I affix my signature.

VIRGIL E. FREDERICK.
